UNITED STATES PATENT OFFICE.

CHESLEY DOM, OF CINCINNATI, OHIO, ASSIGNOR TO THE SAMUEL C. TATUM COMPANY,
OF CINCINNATI, OHIO, A CORPORATION OF OHIO.

TEMPORARY BINDER.

1,118,273.

Specification of Letters Patent.

Patented Nov. 24, 1914.

Application filed October 7, 1912. Serial No. 724,420.

To all whom it may concern:

Be it known that I, CHESLEY DOM, a citizen of the United States, residing at Cincinnati, in the county of Hamilton and State of Ohio, have invented certain new and useful Improvements in Temporary Binders, of which the following is a specification.

My invention relates to an improvement in loose sheet binders, preferably of a type in which a follower or movable cover member is slideable upon posts secured to a base, with the base likewise serving as a cover member. In binders of this class the follower or movable member is free to move in one direction, that which binds the loose sheets between the cover members and automatically locks against movement in an opposite direction, with a release in such opposing direction manually effected.

The object of my invention is to provide a follower or movable member of a loose sheet binder slideable upon posts and locked to the posts by a reverse action or pressure and in which the locking instrumentalities are comprised in a wedge member disposed angularly relative to the post with which it engages to impinge against the same and frictionally lock therewith in one direction of movement, automatically releasing in a reverse movement, with the wedge qualifying as a lever for controlling a positive release.

Another object of my invention is to provide a series of clamping members within a casing of the follower member of the loose sheet binder, through which impaling posts are adapted to project, one for each locking member, with the locking member producing a wedge-like action between the follower member and post, to resist a reverse movement of the follower member upon the post, while free to move in a forward direction, the clamp qualifying as a lever and capable of being rocked and maintained in a released position, and a movable member slideable within the casing and accessible from the exterior, adapted to engage all of the locking members of the binder for simultaneously controlling the same to swing the same into and out of operative position.

Another object of my invention is to provide a follower member of a loose sheet binder with a notch or notches depending upon the number of impaling posts with which the follower engages, with the

notches formed transversely relative to the movement of the follower member upon the posts, and angular, so that the locking member will have a tendency to bridge or gap the notch and prevent lateral displacement of the follower member from its post when the locking member is in a post-binding position, and in an alternate released position effect a notch clearance offering easy and convenient removal and insertion of the follower member upon the post or posts when a plural number of binding elements are employed.

The follower is provided with a locking member movable to and from a position of engagement with the posts, and capable of locking therewith in one direction of movement, and at the same time bridge the notch at the outer side of the post to prevent displacement of the follower and posts.

As a specific characteristic it is the object of my invention to provide a follower of a loose sheet binder with an angular notch extending from one edge thereof to provide engagement with the post at any point, with a wedge member qualifying as a lever mounted on the follower, one for each post, notched to partially envelop a respective post and partially close the notch gap and circumferentially bind the posts within the follower. The follower is provided with a slide member of integral form having elastic and non-elastic portions, engaging each of the wedges and alternately with the lever ends, to swing the same into and out of post engagement, and maintaining the same under tension during post engagement toward a binding direction.

The features of my invention are more fully set forth in the description of the accompanying drawings, forming a part of this specification, in which:—

Figure 1 is a top plan view of the clamping end of the follower or cover member of a loose sheet binder illustrating the same in a clamped position upon a pair of impaling posts with the posts shown in section. Fig. 2 is a section on line α , α , Fig. 1. Fig. 3 is a detailed top plan view of the locking members mounted in position upon a base plate of the follower with the casing covering the same removed. Fig. 4 is a detailed plan view of the sliding member, serving as a latch plate for controlling the operation of

the post clamping members. Fig. 5 is a section similar to Fig. 2, showing the sliding latch plate of modified form.

In the drawings the stationary cover member or base of the loose sheet binder, which carries the impaling posts is omitted, but the same is of common and well-known construction, and therefore, elaboration is not essential herein, as the same is common in all binders of this class. In general, however, it is comprised in a plate inclosed within a covering, having a cover flap hinged thereto, with a pair of impaling posts secured and projected from the plate. 1 and 2 represent such impaling posts upon which the follower or cover member 3 moves and is clamped. The follower preferably comprises a plate 4 usually inclosed within a cloth covering, and to which a cover flap 6 is hinged, the covering forming the hinge whereby the binder in use presents a book embodiment, irrespective of the number of sheets clamped between the cover elements, and reference may be had thereto, without disturbing the binder members.

The plate 4 is provided with the angular notches 7, 8 through which the posts 1, 2 respectively project, the angular disposition of the notches functioning to permit a lateral removal of the follower member 3 from the posts when the locking instrumentalities are in a released position, and also functions in preventing such lateral movement when the locking instrumentalities are in an active position. This feature, however, will be more fully described and it is obvious that this notch feature is not material to certain aspects of the invention in which lateral removal of the follower member is not a characteristic of the binder. An orifice could serve equally as the angular slot or notch to receive the posts, in which instance vertical movement of the follower member is necessitated in inserting or withdrawing the same from the posts, and therefore, I do not wish to be limited to a lateral removable type of follower cover member, except in so far as this feature may be embodied in the claims.

9 represents a casing secured to the upper surface of the plate 4. The casing at its ends is provided with projecting tangs adapted to pass through orifices in the plate 4 and bent parallel with the lower surface of said plate, providing fastening means for securing the casing to the plate. It is also provided with the angular notches 10, 11, coinciding respectively with the notches 7 and 8 of the plate 4.

12, 13 represent lock lever members, one for each post, provided with tangs 14 projecting from the intermediate portion thereof, which engage into orifices 15 formed in the plate 4. This provides a loose socket connection, and serves as a pivot for the lever. One edge of each tang is straight and

positions parallel with an adjacent post and when engaged with the wall of the orifice forms an abutment for one limb of the lever when functioning as a wedge. The second edge 17 developing in an arc, offering clearance for a free rocking or swinging movement of the lever.

It is obvious that the lock lever or wedge member can be constructed to serve only as a wedge, other instrumentalities than those shown being provided for producing a manual release of the member from a post engagement, without departing from the general characteristics or features of my invention. The lever formation herein illustrated defines one type designed for the specific manual releasing mechanism, enabling an elastic element to be employed productive of multiple functions having inherent advantages.

The wedge limbs of the lever or lock members 12, 13 are provided with notches 19 corresponding in outline somewhat to the radius of the post, so as to produce an overlapping edge capable of protruding into the notch clearance of the follower to prevent longitudinal displacement of the follower when engaged with the posts, and thereby prevent radial removal of the follower or movable cover member from the post when the wedge member or limb is in a locking position.

As illustrated, the wedge only partially blocks the gap of the angular notches, which is sufficient to achieve the result desired, and enables a very restricted movement of the wedge member to effect a release and clearance of the notch gap. The angular disposition of the notch directs the release of the follower member toward the wedge and together with one edge of the notch in the wedge-member produces a very substantial circumferential inclosure of the post within the follower member. This, in service, is substantially equivalent to a complete bridging of the notch against radial longitudinal movement or a relative angular movement of the cover or follower member, which would effect a removal thereof from the posts and with a further result that the parts have a tendency to more securely lock together against any accidental radial movement of the cover member.

To simultaneously move the pair of wedging levers I provide the slide member 20 slidably mounted to the interior of the casing 8 by a button 21 having a shank 22 projected through an oblong slot 23 in the casing 8, and riveted or fixed to the slide 20. This slide is preferably formed of flexible material, in order that its free ends, which engage respectively with the lever members 12 and 13 may function as springs for yieldingly maintaining the wedge limbs of the lever members in their post-engaging posi-

tions. The ends of the slide are preferably provided with a corrugation adapted to seat within a notch or groove 26 in the wedge limb to offer resistance against a free movement of the slide 20 toward a releasing direction, and thereby prevent accidental displacement of the parts.

As shown in Fig. 2, the end of the slide 20 is engaged with the wedge limb of the levers, 10 bringing the limbs into engagement with the post. Moving the slide to the left would bring the slide ends into engagement with the opposite limbs of the slide levers, causing a downward pressure thereon, swinging 15 the levers to a post-disengaging position.

To insure such releasing movement, the ends of the slide 20 are turned upwardly, so as to engage with the upper wall of the casing 8, which bend reinforces such end, producing a wedge-like action between the limb 24 of the lever and the upper wall of the casing during a releasing movement of the slide 20, forcing the levers to move or swing 25 away from their post engagement. This insures a positive release of the locking elements, should an exceptionally tight bind result from a wedge-locking action, the end 30 of the slide operating in such instance as a rigid non-elastic member.

As shown in Fig. 4, the slide 20 at its intermediate portion is provided with the V-rib 25 serving as a reinforcement thereof, strengthening such portion and enabling the 35 production of the slides from flexible material as an integral element having portions rigid against flexation, while portions thereof are yielding, which is quite an advantage in its manufacture, as the whole is a stamping.

It will be seen that the various elements are united and mounted in position without the employment of auxiliary fastening instrumentalities, enhancing its durability and convenience of assemblance, with a minimum 45 number of parts.

Having described my invention, I claim:—

1. A loose sheet binder of the character disclosed, combining a base, posts secured thereto, a follower mounted on said posts, wedge elements loosely supported upon the follower, adapted to bind between the follower and posts in one direction of movement of the follower, releasing in a reverse movement, each wedge element having an 50 abutment engaging into an orifice formed in the follower to provide a pivotal connection therewith and a wedge actuator longitudinally slidable upon said follower having yielding and transversely crimped extremities, each adapted to engage into a coincident recess in said wedge elements respectively in their post binding position.

2. A loose sheet binder of the character disclosed, combining a base, posts secured thereto, a follower movably mounted on said 55

posts, a wedge element for each post, having an abutment projected therefrom loosely seating within the follower, and arranged to engage with the post to bind the elements in a movement of the follower upon the post in 70 one direction relative to the base and a wedge actuator longitudinally slidable upon said follower having yielding and transversely crimped extremities, each adapted to engage into a coincident recess in said wedge 75 elements respectively in their post binding position.

3. A loose sheet binder of the character disclosed, combining a base, posts secured thereon, a follower movably mounted on 80 said posts, a wedge element for each post having one end notched to partially envelop the post, its opposite end provided with a protuberance loosely seating in an orifice in said follower, possessed of pivotal 85 and abutment functions in locking and releasing the wedge post engagement and a wedge actuator longitudinally slidable upon said follower having yielding and transversely crimped extremities, each adapted 90 to engage into a coincident recess in said wedge elements respectively in their post binding position.

4. A loose sheet binder of the character disclosed, combining a base, posts secured 95 thereon, a follower movably mounted on said posts, a wedge element for each post having one end notched to partially envelop its post, its opposite end having tang protuberances, each seating loosely within an 100 orifice formed in said follower possessing universal pivotal and abutment connection therewith for locking and releasing the wedge post engagement in movements relatively away from and toward the base and a 105 wedge actuator longitudinally slidable upon said follower having yielding and transversely crimped extremities, each adapted to engage into a coincident recess in said wedge 110 elements respectively in their post binding position.

5. The combination of a binding plate having a post-receiving aperture, a post engaging through said aperture, a lever fulcrumed on said plate having a limb thereof 115 adapted to engage with said post and bind therewith, an elastic member having a non-elastic portion movable to engage said lever alternately upon opposite sides of its fulcrum to yieldingly depress said limb toward its post-engagement, and the non-elastic portion of said member capable of engaging between said lever and a surface on said plate to positively depress the opposite limb of said lever.

6. The combination of a binder plate having a post receiving aperture, a post engaging through said aperture, a lever fulcrumed on said plate, having a limb thereof adapted to engage with said post to bind 120 125 130

therewith, an elastic member movable to engage said lever upon opposite sides of its fulcrum to yieldingly swing said lever in one direction and engage between the lever and a surface of said plate in an alternate position to positively swing said lever in an opposite direction.

7. The combination of a binder plate having a post-receiving aperture, a post engaging through said aperture, a lever swingingly mounted on said plate, one limb thereof adapted to engage with said post, an elastic member having a non-elastic portion movable to opposite sides of the fulcrum of said lever to swing the same, the non-elastic portion capable of engaging between said lever and a rigid portion of said plate to forcibly swing said lever.

8. The combination with a binding plate, an impaling post capable of projecting through said plate, a lock lever comprising relatively angularly disposed limbs having tangs projected at right angles therefrom at the juncture of said limbs, each engaged within a circular orifice in said binding plate, so as to function as an abutment and fulcrum for said lock lever, with one of said limbs notched to partially envelop the post, and a yielding actuator adapted to alternately engage said lever limbs to rock the same.

9. The combination of a binder plate having a notch extended angularly therein from one edge, a post engaging into said notch, a lock lever on said binding plate swingingly mounted to engage and partially envelop the post and obstruct the post exit through the notch and an actuator adapted to engage said lever alternately upon opposite sides of the fulcrum to rock the same.

10. The combination of a binding plate having a notch extended angularly therein from one edge, a post inserted in said notch and projected through said binding plate, a wedge lever pivoted upon said binding plate adapted to swing so as to lock the plate against movement on said post in one direction, releasing in an opposite movement, with the wedge lever arranged to overlap the post across the notch gap, and capable of being swung to a post-releasing and a notch-unobstructing position and an actuator adapted to engage said lever alternately upon opposite sides of its fulcrum to rock the same.

11. The combination of a binding plate having a notch extended angularly therein from one edge, a post inserted in said notch and projected through said binding plate, a wedge lever pivoted upon said binding plate adapted to swing so as to lock the plate against movement on said post in one direction, releasing in an opposite movement, with the wedge lever arranged to overlap the post across the notch gap, and

capable of being swung to a post-releasing and a notch-unobstructing position, and a member movable on said binding plate, having a crimped extremity engaging said wedge lever alternately on opposite sides of its fulcrum for swinging the same to post engaging and releasing positions.

12. The combination of a hollow binding plate having a notch extended angularly therein from one edge, a post inserted in said notch and projected through said binding plate, a post binding lever pivoted within the binding plate with one limb thereof adapted to swing to lock the plate against movement on said post in one direction, releasable in an opposite movement thereof, and partially envelop the post across the notch gap, and a slide member movable within said binding plate to opposite sides of the lever fulcrum to swing the same to post engaging and releasing positions, with its extremity crimped to engage said plate and a limb of the lever to positively rock the lever.

13. The combination with a casing follower binder member apertured to receive a post, a post-engaging lever fulcrumed within said binder member, and a lever actuating member within said binder member movable to alternate lever engaging positions upon opposite sides of its fulcrum, to yieldingly urge said lever toward a post-engaging direction in one position, and engage said lever and binder member in a second position to positively swing said lever in an opposite post-releasing direction.

14. A loose sheet binder of the nature disclosed, combining a base, a pair of impaling posts secured thereto, a follower movably mounted on said posts, a pair of levers swingingly mounted on said follower, one for each post, one limb of each functioning as a wedge between the follower and respective posts to bind the parts against one direction of movement, a slide member mounted on said follower having elastic limbs and non-elastic extremities, each engaging a lever on one side of its fulcrum and movable to an opposing side, functioning in one instance as a tension means, and in a second as a rigid member to engage between the levers and a surface of said follower for swinging the levers.

15. A loose sheet binder of the nature disclosed, combining a base, a pair of impaling posts secured thereon, a follower movably mounted on said posts having notches extended angularly therein from one edge, each to receive a post, a swinging wedge member mounted on said follower movable to and from a position in which it will lock the follower against movement on said post in one direction, releasing in an opposite movement, with the wedge members each obstructing the notch gap in one

position, a slide member on said follower engaging with said wedge members to simultaneously swing the same into and out of an operative position.

- 5 16. A loose sheet binder of the nature disclosed, combining a base, a pair of impaling posts secured thereon, a follower movably mounted on said posts having notches extended angularly therein from
10 one edge, each to receive a post, a swinging wedge member for each post pivoted near its center on said follower and movable to and from a position in which it will lock the follower against movement on said posts in
15 one direction, releasing in an opposite move-

ment, with the wedge members each obstructing the notch gap in one position, a resilient member slideable on said follower engaging said wedge members alternately on opposite sides of their fulcrum to simultaneously swing the same into and out of operation and maintain the same under post-engaging tension in an operative position.

In testimony whereof, I have hereunto set 25 my hand.

CHESLEY DOM.
